UNITED STATES PATENT OFFICE.

JOHN A. MCANULTY, OF MINNEAPOLIS, MINNESOTA.

PITMAN.

SPECIFICATION forming part of Letters Patent No. 394,280, dated December 11, 1888.

Application filed March 26, 1888. Serial No. 268,547. (No model.)

To all whom it may concern:

Be it known that I, JOHN A. MCANULTY, a citizen of the United States, residing at Minneapolis, in the county of Hennepin and State of Minnesota, have invented certain new and useful Improvements in Pitmen; and I do hereby declare the following to be a full, clear, and exact description of the invention, such as will enable others skilled in the art to which it appertains to make and use the same.

My invention relates to pitmen for connecting cranks or eccentrics, either revolving or rocking, to parts of machinery which are designed to be reciprocated; and it consists in the improved construction and arrangement or combination of parts of the pitman and its connections, which will be hereinafter fully disclosed in the description, drawings, and claims.

The objects of my invention are, first, to provide improved means for vibrating or reciprocating parts of machinery, and, second, to provide improved means for attaching pitmen to eccentrics, eccentric shafts or cranks in such a manner that rattling and heating of boxes will be prevented and free play allowed to the parts vibrated or reciprocated without binding or unequal wear upon said eccentrics, eccentric shafts or cranks.

In the accompanying drawings, forming part of this specification, wherein the same reference-numerals indicate the same or corresponding parts, Figure 1 represents a side view of the pitman in section, showing it attached to a coupling adapted to be secured to a vibrating or reciprocating part supported in a plane in line with the shaft, the latter being shown in section; Fig. 2, a similar view showing the pitman attached to a coupling adapted to be secured to a reciprocating or vibrating part supported in a plane below that of the shaft; and Fig. 3, a top plan view showing the various positions which the pitman may assume in dotted lines.

In the drawings, the numeral 1 indicates the shaft, having a crank or an eccentric, 2, which may be formed by reducing the shaft, as shown in the drawings, or by attaching an eccentric of larger radius than the shaft, or in any of the well-known ways of forming cranks or eccentrics.

The cylindrical box 3, as shown in section

in Figs. 1 and 2, is formed in two parts and so fitted upon the eccentric as to permit the latter to move or revolve freely within it; also, the upper part thereof may be provided with an oil-cup, 4, adapted to receive and distribute a suitable lubricant to the eccentric and throughout the interior of the box. The two parts of the box have diametrically-opposite conical depressions 5, placed at an angle of about forty-five degrees to the axial line of the pitman and the plane of the mechanism to be reciprocated.

6 represents the pitman, which is formed at its inner end with a curved head, 7, which passes around more than half of the box, preferably beneath the same. A point or pivot, 8, is formed upon the inner side of this curved head, and is so fitted into the depression 5 in the lower part of the box as to pivot freely therein laterally; also, the extreme end of this curved head is formed with a screw-threaded opening, 9, at a point diametrically opposite the point or pivot 8. A set-screw, 9', which also acts as a pivot, passes through this opening and fits with its conical end in the depression 5 in the upper part of the box. A binding-nut, 10, firmly holds the set-screw in its adjusted position. By tightening this set-screw a perfect adjustment of the two-part box to its crank or eccentric is effected and wear compensated for.

The outer end of the pitman or connecting-rod 6, which is attached to the object to be vibrated or reciprocated, is preferably bent at a right angle to the remaining portion of said pitman, as at 11, the end of the bent portion being formed with a ball, 12, which is adapted to fit in a suitable ball-and-socket joint or coupling, 13, attached to the part to be vibrated or reciprocated, thus permitting said part to have a universal movement about the ball of said pitman.

In Fig. 1 of the drawings the outer end of the pitman is turned upward and then curved downward, this form being used when the part to be reciprocated or vibrated is supported in a plane with the eccentric-shaft; also, when said part is arranged in a plane above or below that of the shaft—an instance of it below being shown in Fig. 2—said outer end of the pitman is bent at a right angle to its body portions, either upward or down-

ward. These bends in the pitman cushion the shock ordinarily incident to the reciprocating or vibrating frames employed in various kinds of machines—such as middlings-purifiers, feed-regulators, and grain-cleaners—especially in those machines in which the parts moved are rapidly reciprocated. This cushioning or avoidance of jar is due to the spring or resiliency of the metal forming the bends of the pitmen, which enables me to dispense with the springs ordinarily employed for supporting shaking frames in machines of the kind just named.

It will be obvious from the foregoing that the ball-and-socket joint or coupling forming the connection between the part reciprocated or vibrated and the pitman, together with the pivots arranged at an angle to the axial line of said pitman and forming the connection between the inner end of the pitman and the eccentric, will allow the part being reciprocated to deviate from a line at right angles to the shaft, as shown in dotted lines in Fig. 3; that all irregularities in the motion of said reciprocating or vibrating part will be taken up or compensated for; that uneven wear upon the eccentric and the two-part boxing, due to heating from the binding or cramping and rapid movement of the parts, is entirely avoided, and also that rattling of the joints or couplings is prevented.

This construction of pitman is especially adapted to be used in machines of the character above referred to for the treatment of grain or its products in any form, since in that class of machines the principal parts require reciprocating or vibrating movement and cushioning, as they are subjected to varying pressures or loads of stock; but, as is evident, my generally improved pitman, with its curved head pivoted to the crank or eccentric at diametrically-opposite points, which are arranged at an angle to its axial line, may be employed in any mechanism in which a pitman is required to permit of lateral play.

I do not herein claim the combination of an eccentric, a box mounted thereon, and a laterally-movable pitman provided with pivots at its inner end arranged at an angle to its axial line, and provided near its outer end with a spiral spring, which is lengthwise compressible and expansible and laterally and vertically yielding or movable, as the same forms part of a similar invention, for which I have filed application for Letters Patent simultaneously herewith, Serial No. 268,548; also, I do not claim the combination of a crank-pin and a pitman connected thereto by means of a ring, and a box within said ring which is pivoted upon two points that are coincident with the axis of said pitman, as this construction does not permit of the wide range or freedom of lateral movement of the pitman employed by me and provided with pivots arranged at an angle to the axial line thereof.

Having thus fully described the construc-

tion and operation of my invention, what I claim as new is—

1. The combination, with an eccentric and a box mounted thereon, of a laterally-movable pitman provided at its inner end with pivots arranged at an angle to its axial line, substantially as and for the purpose described. 70

2. The combination, with an eccentric and a box mounted thereon, of a laterally-movable pitman provided at its inner end with pivots arranged at an angle to its axial line, and having its outer end formed into an elastic or spring portion, substantially as and for the 80 purpose described.

3. The combination, with an eccentric and a box mounted thereon, of a laterally-movable pitman provided at its inner end with pivots arranged at an angle to its axial line, and having its outer end bent at a right angle and formed into an elastic or spring portion, substantially as and for the purpose described. 85

4. The combination, with a pitman formed with a curved head having diametrically-opposite pivots at its end and inner side, which are arranged at an angle to its axial line, of an eccentric, and a box mounted thereon and formed with diametrically-opposite depressions in which said pivots fit, substantially as and for the purpose described. 90

5. The combination of an eccentric and a cylindrical box mounted thereon and provided with diametrically-opposite depressions, which are arranged at an angle to the axis of said eccentric, with a pitman having a curved head formed with a pivotal point on its inner side resting in one of said depressions and having a screw-threaded opening in its outer end, and a pointed set-screw having its end resting in the other depression, substantially as and for the purpose described. 100

6. The combination of an eccentric and a two-part box mounted thereon, with a laterally-movable pitman provided with pivots arranged at an angle to its axial line, one of said pivots being a set-screw for adjusting said two-part box and compensating for wear, substantially as and for the purpose described. 110

7. The combination of an eccentric-shaft and a two-part box mounted thereon, with a laterally-movable pitman provided with pivots arranged at an angle to its axial line, one of said pivots being a set-screw for adjusting said two-part box to compensate for wear, and a clamping-nut for holding said set-screw in its adjusted position, substantially as described. 120

8. The combination of an eccentric and a cylindrical box mounted thereon and provided with diametrically-opposite depressions in its sides, which are arranged at an angle to the axial line of said crank or eccentric, with a laterally-movable pitman having a curved head provided with diametrically-opposite pivots at its end and on its inner side, which fit in said depressions, and formed at its outer 130

end with a bent elastic or spring portion, substantially as described.

9. The combination of an eccentric, a box mounted thereon, and a laterally-movable pit-
5 man provided with pivots at its inner end, and formed at its outer end with a bent elas-
tic or spring portion having a ball at its end, with an object or part which is adapted to be reciprocated or vibrated, and which is pro-

vided with a ball-and-socket joint or coup- 10
ling, substantially as described.

In testimony whereof I affix my signature in presence of two witnesses.

JOHN A. McANULTY.
